UNITED STATES PATENT OFFICE.

GEORGE E. TURNER, OF NEW LEXINGTON, OHIO.

HYDRAULIC LEVELING AND MOVING DEVICE.

Application filed January 5, 1926. Serial No. 79,439.

This improvement relates to dredges, excavating and similar machines, and particularly those employing large revolving shovels which are required to be moved, 5 wherein it is also desirable that leveling mechanism be employed.

An object of this invention is to devise hydraulic moving and leveling mechanism suitable for heavy types of machines such as 10 dredges, mining machines and similar appliances employing heavy shovels or similar devices. There is illustrated and described herein a machine with a stationary circular base having an upper circular revolving portion, such that the strains and stresses are 15 evenly distributed around the circular part, and the hydraulic moving and leveling mechanism is so constructed and arranged that the machine can be moved with a minimum of labor and expense and with a minimum of risk and in an improved manner.

Referring to the drawings, Fig. 1 is a side elevation view, some of the parts at the left side being shown in section, and Fig. 2 is a 20 plane view, some of the parts being removed to show more clearly the remainder of the parts.

The stationary circular base is marked A (see Fig. 1) and the revolving circular member is marked B and this revolving member B is supported by the stationary base through the instrumentality of a ring member C, there being shown rollers partly 25 around the ring member and these rollers are preferably continuously placed around the ring member and in close relation so as to support the revolving member B evenly 30 throughout its circumference. At the left hand side of Fig. 1 there is shown in section 35 a rail X of circular shape secured to the upper revolving member B and a circular rail W secured to the lower stationary member A, and the rollers of the ring member C are located between those two rails so that 40 the rolls or wheels will rotate with a minimum of friction as indicated in Fig. 1. The parts A and B are formed of heavy rolled 45 plates and angles braced and held in place by horizontal beams D and radial beams E, 50 and segmental plates F (see Fig. 2). The circular revolving member B may preferably have a rectangular extension indicated by V (see Fig. 1) to accommodate a part of the operating mechanism and to carry ballast 55 when necessary to give balance to the revolving part of the shovel machine, and at the

center of the stationary and revolving member there is shown a large pintle or casting G (see Fig. 2) and a corresponding pintle or casting may be secured to the stationary base 60 and these two parts interlocked in any ordinary way to permit the member B to revolve upon an axis projecting from the member A and these two parts, A and B, are preferably held at all times together and in 65 the same circular relation one to the other. These circular frames avoid the stresses and strains which have heretofore resulted from forming the base member and the revolving member with right angle connections and 70 joints that are subject to defects due to the loosening and shearing of the rivets. In this circular type it will be apparent that the rails W and X are at all places and throughout their entire length or circumference directly over or under and in line 75 with the center of the web sections of the circular frames and this construction is calculated to distribute the weight much more uniformly over all the rollers on which the 80 upper parts revolve than has heretofore been possible.

Attached to the lower circular stationary base A and on the outside thereof are a 85 plurality of heavy hydraulic jacks, in this case there being shown six jacks in all, and two of these jacks marked H are in the line of direction of the movement of the machine, being placed on a central line through the base A, one being placed directly opposite the other. The cylinders of jacks H contain rams or plungers fitted in the ordinary way with packing leathers and of such size and area that when thrust downwardly 90 by oil or other fluid supplied by a high pressure pump, they will raise or support the entire weight of the machine, and this operation of raising the entire machine by means of a high pressure pump is only necessary when the entire mechanism assumes 95 a position such that it requires the machine to be raised as hereinafter more fully explained. There is illustrated herein four auxiliary hydraulic jacks marked I, which are similar to the main jacks H, and these 100 auxiliary jacks are also provided with plungers and leather packing, and these jacks are not so large as the main jacks, but are of sufficient size to support the entire weight of the machine by means of oil or 105 other fluid which may be fed to the jacks, and this oil or fluid may be fed to them by 110

means of the same or another pressure pump as that furnishing oil or fluid to the main jacks, but there is preferably illustrated herein a separate tank associated with the auxiliary jacks, and the oil or fluid from said tank is fed by gravity to the auxiliary jacks, these tanks being marked J (see Fig. 2). The fluid passes by gravity from said tanks J through pipes O and O', and check valves P and P' to the spaces in the cylinders above the rams or plungers, keeping these spaces full at all times, and the tanks are of such size as to hold sufficient fluid to fill entirely the auxiliary jacks. Whenever the rams or plungers are fully extended; the fluid passing to the auxiliary cylinders cannot return to the tanks J except through the valves G—I, which are located in a bypass in the pipe lines O and O' (see Fig. 1), and the arrangement is such that these valves are intermittently operated to enable the weight of the machine to be shifted to the auxiliary jacks when it is desired to shift the supporting pads for the main jacks as hereinafter more fully described.

In a general way it is to be understood that normally the weight or load of the entire mechanism is evenly supported by the main and auxiliary jacks and this condition obtains when the machine is being operated in a normal way. When, however, it is desired to advance the machine to a better position for normal operation, the machine travels on the pads of the main hydraulic jacks, and during that movement the entire weight of the machine is shifted to the main hydraulic jacks, the auxiliary jacks having to be relieved from the weight of the load so that the auxiliary jacks and pads can travel with the travel of the machine, but when it becomes necessary to advance the machine in order to change its working position, the entire weight of the machine is then shifted to the auxiliary jacks and the main jacks are thereby relieved of the weight or load, and while the main jacks are thus relieved of the weight or load, the pads associated with the main jacks are advanced to a new position so that the machine can thereby be readily moved from place to place without the expense and labor incident to tearing up the tracks and replacing the same as heretofore commonly done.

With this explanation it will be seen that there is employed a pressure pump marked L (see Fig. 1), which is placed on the top of the upper revolving member B, and that it puts fluid under pressure from the supply tank K and supplies same to the main jacks H and H' through the pipe Y, which extends downwardly as indicated in Fig. 1, and this pressure pump is also operated whenever it is necessary to raise the entire mechanism in order to overcome difficulties due to the fact that the plungers of the aux-

iliary jacks may become completely extended so that no further movement can be made by those plungers until the entire machine is raised. The pipe Z is shown connected to the pipe Y, and this pipe extends through a larger downwardly extending pipe marked X', which serves to return the fluid as hereinafter more fully explained. The plungers or rams in the main cylinders rest in sockets in the upper or top side of the truck frame Q, and attached to the under side of these truck frames Q are shown horizontally disposed cylinders marked T, which have piston rods projecting through each end of the cylinders, the ends of the pistons being secured to the pads M, which rest upon the ground, and these are large heavy track pads or platforms made preferably of wood and steel on which the trucks Q connected with the main jacks H travel, there being stops S (see Figs. 1 and 2) which limit the travel of the truck frames Q upon the pads, and there are preferably shown wheels R which travel upon the rails S, which are in turn secured to the truck pads M, and there are restraining or guard rails S' which, together with the stops S, prevent the trucks from leaving the pads, or from traveling on any other than a straight line.

The pads N are square or rectangular bearing pads made preferably of wood and steel with socket castings in which the rams or plungers of the auxiliary jacks I rest, and these pads are shown loosely shackled in an ordinary and usual way to the rams or plungers so that the pads may be moved forward or backward with the movement of the machine, and yet always held against the rams or plungers.

Referring to the pipe line connections for the fluid from the supply tank K, it will be seen that the lower end of the pipe Y is secured to branch pipes Y', which extend forwardly and rearwardly from a central point, and the vertical pipe X' is connected to forwardly and rearwardly extending pipes X''. At the lower ends of the vertical pipes Y and Z and at the upper ends thereof there are shown flexible turning joints in order to accomodate the parts to the turning motion incident to the character of the machine. The branch pipes Y' extend to special operating valves C', and through branch pipes marked B' (see Fig. 1), and also to the operating valves A', which control the flow of the fluid to the main hydraulic jacks. Through the valves C' fluid under pressure is passed to either end of the horizontally disposed cylinders T attached to the under side of the trucks Q, and these cylinders T are at all times full of fluid and when fluid is allowed to enter one end or at one side of the pistons an equal quantity of fluid escapes or is exhausted from the opposite end

- or other side of the piston, this released fluid passing back to the supply tank K through the pipes X'' and X', there being shown at the top of Fig. 1 a pipe line which extends from the pipe X' to the tank K, and connections are made from this pipe to the pump side of the pressure pump and connections are made from the pump to the pipe line Y so that when the entire mechanism is to be understood the same operation will occur when corresponding parts are operated. Either one or both of the valves C' are then open, letting the fluid under pressure pass from the pump L into the forward end or ends of the cylinders T, which thereby propels the cylinders and the truck frames to which they are attached forwardly toward the ends of the track pads, to which the piston stem or stems are attached at UU, thus carrying the machine forward and bringing the same to a position where the bucket will be closer to the material to be excavated, and manifestly, when fluid under pressure is entering the front end of these cylinders T, the fluid in the other end will escape through proper passages in the valves C' to the return pipe or pipes X'' and X', returning thereby to the supply tank K.
- When the machine has thus been moved forward to such an extent that the wheels have come to rest against the stops S (Figure 1), thereby resulting in the machine reaching the limit of its normal travel, it becomes necessary to move or shift the track pads M to a different position, in order to adapt the machine for further normal movement, and to accomplish this movement of the pads M, the valves G' in the bypass pipes are closed and the valves A' (Fig. 2) are then opened, and when this is done the entire weight of the machine is shifted to the auxiliary jacks I, the jacks H having been relieved from the load or weight, and this also applies to the track pads N which will now merely support the weight of the truck frames Q. While the machine is supported in this manner, the valves C' are again opened, but in the opposite direction, letting fluid under pressure into the rear end of the horizontal cylinder T, permitting it to escape from the forward ends, and under this condition the track pads will be pulled forwardly by the rearwardly extending piston stems until the rear stops engage the rear wheels R of a truck frame Q. The valves C' are now closed or set at neutral position, while the valves A' are also closed so that no fluid can escape from the main jacks H and the weight is once more evenly distributed because the mechanism is supported on all the jacks and excavation with the bucket is then resumed.
- It is apparent that in the continual operation of this manner of shifting the weight from the jacks H to the jacks I, and from the jacks I to the jacks H, there is apt to come a time when the escape of oil from the cylinders will allow the rams or plungers to engage the tops of the cylinders, then the pump L will be put into operation and oil
- or other side of the piston, this released fluid passing back to the supply tank K through the pipes X'' and X', there being shown at the top of Fig. 1 a pipe line which extends from the pipe X' to the tank K, and connections are made from this pipe to the pump side of the pressure pump and connections are made from the pump to the pipe line Y so that when the entire mechanism is to be understood the same operation will occur when corresponding parts are operated. Either one or both of the valves C' are then open, letting the fluid under pressure pass from the pump L into the forward end or ends of the cylinders T, which thereby propels the cylinders and the truck frames to which they are attached forwardly toward the ends of the track pads, to which the piston stem or stems are attached at UU, thus carrying the machine forward and bringing the same to a position where the bucket will be closer to the material to be excavated, and manifestly, when fluid under pressure is entering the front end of these cylinders T, the fluid in the other end will escape through proper passages in the valves C' to the return pipe or pipes X'' and X', returning thereby to the supply tank K.
- When the machine has thus been moved forward to such an extent that the wheels have come to rest against the stops S (Figure 1), thereby resulting in the machine reaching the limit of its normal travel, it becomes necessary to move or shift the track pads M to a different position, in order to adapt the machine for further normal movement, and to accomplish this movement of the pads M, the valves G' in the bypass pipes are closed and the valves A' (Fig. 2) are then opened, and when this is done the entire weight of the machine is shifted to the auxiliary jacks I, the jacks H having been relieved from the load or weight, and this also applies to the track pads N which will now merely support the weight of the truck frames Q. While the machine is supported in this manner, the valves C' are again opened, but in the opposite direction, letting fluid under pressure into the rear end of the horizontal cylinder T, permitting it to escape from the forward ends, and under this condition the track pads will be pulled forwardly by the rearwardly extending piston stems until the rear stops engage the rear wheels R of a truck frame Q. The valves C' are now closed or set at neutral position, while the valves A' are also closed so that no fluid can escape from the main jacks H and the weight is once more evenly distributed because the mechanism is supported on all the jacks and excavation with the bucket is then resumed.
- It is apparent that in the continual operation of this manner of shifting the weight from the jacks H to the jacks I, and from the jacks I to the jacks H, there is apt to come a time when the escape of oil from the cylinders will allow the rams or plungers to engage the tops of the cylinders, then the pump L will be put into operation and oil

or fluid will be fed to the main jacks H through the valves A', thus lifting the entire machine, and while the machine is being raised the auxiliary jacks I will automatically be supplied or filled with fluid by gravity from the tanks J. It is to be understood that various modifications might be suggested illustrating the general principle of operation, and it is not intended to limit the invention to any particular location of the valves, nor to any particular manner of grouping or coupling them together, nor any particular way of manipulating the parts.

Having thus described my invention, I claim:

1. In a machine of the character described, a shovel frame with main supporting pads, tracks on said pads, elevating devices above said main pads, carrying wheels connected with said elevating means adapted to run on said tracks, supplemental pads, elevating devices for said supplemental pads, means for operating the main elevating devices thereby relieving the supplemental devices from the weight of the shovel frame, means for operating the supplemental elevating devices for relieving the main pads of the weight of the shovel frame, means for moving the main pads while the shovel frame is supported by the supplemental pads.

2. In a machine of the character specified, a shovel frame with main supporting pads placed in line of movement of said frame, supplemental supporting pads placed at the sides of the machine, elevating devices above said main pads and supplemental elevating devices above said supplemental pads, carrying wheels connected with said first mentioned elevating devices, hydraulic means for operating said first mentioned elevating devices thereby relieving the supplemental devices of the weight of the shovel frame, hydraulic means for operating the supplemental elevating devices, thereby relieving the main pads of the weight of the shovel frame and hydraulic means for moving the main pads while the weight of said shovel frame is carried by the supplemental pads.

3. In a machine of the character specified,

a shovel frame, main pads with tracks thereon placed in the line of movement of said shovel frame, carrying wheels adapted to run on said tracks, main elevating devices connected with said wheels, supplemental pads for supporting the shovel frame placed at the sides of the machine, elevating devices associated with said supplemental pads, whereby the weight of the shovel frame may be supported by all the pads, hydraulic means for operating the main elevating devices for relieving the supplemental pads of the weight of the shovel frame, whereby the carrying wheels may carry the shovel frame along said tracks, hydraulic means for operating the supplemental elevating devices for raising the shovel frame and thereby relieving the main pads from the weight of the shovel frame, hydraulic means for moving the main pads while the supplemental pads support the weight of the shovel frame.

4. In a machine of the character specified, a shovel frame, main pads with tracks thereon placed in the line of movement of said shovel frame, carrying wheels adapted to run on said tracks, main elevating devices connected with said wheels, supplemental pads for supporting the shovel frame placed at the sides of the machine, elevating devices associated with said supplemental pads, whereby the weight of the shovel frame may be supported by all the pads, hydraulic means for operating the main elevating devices for relieving the supplemental pads of the weight of the shovel frame, whereby the carrying wheels may carry the shovel frame along said tracks, hydraulic means for operating the supplemental elevating devices for raising the shovel frame and thereby relieving the main pads from the weight of the shovel frame, hydraulic means for moving the main pads while the supplemental pads support the weight of the shovel frame, pressure devices for restoring the supplemental elevating devices to normal position at predetermined times.

In testimony whereof, I have hereunto set my hand this 26th day of December, 1925.

GEORGE E. TURNER.
